UNITED STATES PATENT OFFICE.

ANTON REICHE, OF PLAUE, NEAR DRESDEN, GERMANY.

CANDY-MOLDING MACHINE.

SPECIFICATION forming part of Letters Patent No. 699,973, dated May 13, 1902.

Application filed October 26, 1901. Serial No. 80,084. (No model.)

To all whom it may concern:

Be it known that I, ANTON REICHE, a citizen of the Kingdom of Saxony, in the Empire of Germany, residing at Plauen, near Dresden, in the Kingdom of Saxony, Germany, have invented a certain new and useful Improved Candy-Molding Machine; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to a candy-molding machine in which the candy-molds are fed automatically through the machine and filled from a suitable candy-containing hopper; and the object of the invention is to provide a machine of this character in which the filling of the candy-molds is done in an efficient and expeditious manner.

To this end the invention consists of a candy-molding machine comprising a frame supported on suitable legs, said frame having parallel beams arranged longitudinally thereon, one of said beams being laterally adjustable, means for laterally adjusting the same, means for feeding the candy-molds successively through the machine, a candy-containing hopper supported on said frame for filling the candy-molds, as will be fully described hereinafter and finally pointed out in the claims, reference being had to the accompanying drawings, in which—

Figure 1 is a vertical longitudinal section of my improved candy-molding machine, showing the front part thereof in elevation and the candy-molds feeding therethrough. Fig. 2 is a plan view of the machine, showing the hopper in longitudinal section and with several of the candy-molds removed. Fig. 3 is a vertical transverse section of the machine, taken through the hopper and showing the feed mechanism cut away. Fig. 4 is a vertical section through the front part of the machine to show the feed mechanism, and Fig. 5 is a detail sectional view of the mouth of the candy-containing hopper and adjacent parts.

Similar letters of reference indicate corresponding parts.

Referring to the drawings, A represents the frame of my improved candy-molding machine, which is supported upon legs A' and is provided with a stationary beam B and an adjustable beam B', which are arranged parallel with each other and longitudinally of the machine and are provided with the ways 55 b on their upper faces, the stationary beam forming one side of the rectangular frame A. The beam B' is laterally adjustable, so as to adapt the machine for the use of candy-molds of various sizes, and the lateral adjustment 60 of the beam is accomplished by means of transverse screw-shafts a, arranged at the ends of the machine and journaled in opposite longitudinal sides of the frame A. The shafts a engage screw-threaded openings of 65 the beam B', so that by the rotation of the screw-shafts the beam is caused to be shifted. The simultaneous rotation of the screw-shafts necessary for the proper shifting of the beam B' is accomplished through a long- 70 shaft a', having at its ends the beveled gears a², meshing with the beveled gears a³, carried on each of the screw-shafts a, as shown in Fig. 1. The screw-shaft at the rear end of the machine is provided with a crank 75 a⁴, through which motion is transmitted to the shafts for shifting the beam B'.

At the front end of the machine is a rack in which the candy-molds are arranged one above another and from which they are fed 80 through the machine by a suitable feed mechanism. This rack is composed of standards, preferably of angle-bars, supported upon the beams B' and the brackets C. The standards D are secured stationarily on the beams, 85 and the standards D' are adjustably secured on the brackets C, said brackets being supported on the front end of the frame and projecting therefrom in line with the beams. The lower ends of the standards D are sup- 90 ported above the beam by the brace d, so that the molds can be fed from the rack. The adjustable standards D' are provided with the base portions d', which are secured to the brackets C by means of the bolts d², 95 that pass through the slots d³ of the brackets. By reason of the rack being adjustable 100

molds of various sizes can be used in the machine.

The feed mechanism is arranged adjacent the stationary standards D and consists of 5 companion feed-rolls e e', which are preferably of yielding material, such as rubber, and the rolls e are frusto-conical, while the rolls e' are cylindrical and have a portion of their curved surfaces exposed in the ways b, so as 10 to engage the end edges of the mold. Each beam is provided with a frusto-conical roll and a cylindrical roll, the former of which is arranged under the lower end of one standard D, while the latter is slightly beyond the 15 same. These companion rolls are mounted upon vertical shafts that carry at their lower ends the gears e², meshing with the gears e³, so as to impart similar rotary motion to the rolls. Each gear e³ is mounted upon a vertical shaft e⁴, that carries at its lower end a gear e⁵, that meshes with the worm e⁶ upon the shaft F, that extends transversely of the machine. As the companion rolls carried upon the beam B' are movable therewith, it 25 is necessary to provide for the lateral shifting of its corresponding worm e⁶, which is accomplished by slidably keying the worm to the shaft F by means of a feather f, as shown in Fig. 4. The movement of the worm upon 30 the shaft F takes place by virtue of the gear e⁵ meshing therewith, which moves with the beam B'.

Midway between the ends of the machine is supported a candy-containing hopper II, 35 that extends transversely the full width of the frame of the machine and which is secured to the upper ends of the supports h, that are guided by the vertical standards h', secured to the frame of the machine. At the 40 lower ends of the standards h' are slots h², through which project lugs h³ of the supports h. The lugs h³ are provided with threaded openings that engage the vertical screw-shafts g, which are journaled in the brackets g' of 45 the frame and carry at their lower ends the beveled gears g², which mesh with the beveled gears g³, provided at opposite ends of the shaft G, having a crank G' at one end thereof. By means of this latter mechanism 50 the hopper is adapted to be adjusted vertically in proper relation to the candy-molds.

Upon the adjustable beam B' is provided a yoke-like support I, to which is secured and arranged within the candy-containing hopper II a movable partition I', that is yieldingly connected with the yoke by means of the spring i and is guided by the rods i', that project vertically from the upper end of the movable partition through openings in the 60 top of the yoke-like support I. The movable partition I' is adapted to move with the adjustable beam B, so that the length of the portion of the hopper that contains the candy will always correspond to the length of the 65 molds. The hopper is preferably constructed of metal and is provided with a jacket II', that is connected with a heating apparatus

supported at one side of the hopper, so as to provide for the circulation of water at a suitable temperature around the hopper II in order to keep the candy contained in the hopper in a proper consistency. 70

The bottom of the hopper is provided with a longitudinal mouth having the converging portions m. At the rear side of the mouth is provided an adjustable lip m', so as to regulate the size of the opening for the discharge of the candy from the candy-containing hopper. The adjustment of the lip m' is accomplished by means of a rod m², extending longitudinally of the lip and supported on the candy-containing hopper, as shown in Figs. 3 and 5. The rod m² carries at opposite ends spur-wheels m³, that mesh with the racks m⁴ on the adjustable lip m', the outer end of said rod being provided with a handpiece m⁵. Extending in inclined direction from the rear part of the mouth of the hopper is a strickler n, that is preferably of a resilient material, such as spring sheet metal. The strickler end extends transversely the full length of the machine and is secured to the projections n² on the supports h and is adapted to rest with its lower edge upon the molds as they pass through the machine. The beams are provided with plates n', that are arranged between the discharge-mouth of the hopper and the strickler, so as to prevent the candy from discharging at the ends of the strickler. 85 90 95

In operation of the device manual or motor power may be used. The movable beam is adjusted according to the length of the mold desired to be used in the machine. The adjustable standards of the candy-mold rack are adjusted to suit the width of the candy-molds. The candy-hopper is adjusted vertically, according to the thickness of the molds. The molds are placed one upon another in the rack, the lower mold arranging itself in contact with the feed-roll e, which engages the end edges of the mold, and by operating the feed mechanism the lower mold is fed forward and engaged by the cylindrical feed-roll e' until the lowermost mold is moved out of the rack, and the mold next above is engaged by the feed-roll e and moved forward into contact with the first mold, which causes it to move forward along the ways on the upper faces of the beams B B'. In this manner the mold that is in engagement with the feed-roll causes the preceding molds to move forward through the machine and passing under the discharge-mouth of the candy-containing hopper to be filled, the strickler n' serving for the purpose of compressing the candy into the molds and smoothing off the candy uniformly. 100 105 110 115 120 125

Having thus described my invention, I claim as new and desire to secure by Letters Patent—

1. In a candy-molding machine, the combination, of a suitably-supported rectangular frame having longitudinally-arranged beams thereon, said beams being provided with ways,

means for laterally adjusting one of said beams, and a mold-rack supported on said beams at one end of the machine, substantially as set forth.

5 2. In a candy-molding machine, the combination of a rectangular frame having a stationary beam and a movable beam, ways provided on said beams, means for laterally adjusting said movable beam, and rack-stands secured at one end of the machine, substantially as set forth.

10 3. In a candy-molding machine, the combination, with a rectangular frame, of a stationary beam and a movable beam, said beams being provided with ways, means for laterally adjusting said movable beam, and stationary and adjustable rack-standards secured on said beams and suitably-provided brackets, said adjustable standards being secured on said brackets, substantially as set forth.

15 4. In a candy-molding machine, the combination, with a rectangular frame, of a stationary beam and a movable beam, said beams being provided with parallel ways, means for laterally adjusting said movable beam, stationary and adjustable standards of angle-bars, and slotted brackets secured at one end of the frame in line with said beams having 20 said adjustable standards adjustably secured thereon, substantially as set forth.

25 5. In a candy-molding machine, the combination, with parallel beams provided with suitable ways, of a frusto-conical engaging 30 roll on each beam, a cylindrical roll adjacent to said frusto-conical roll, and means for actuating the same, substantially as set forth.

35 6. In a candy-molding machine, the combination, with beams having parallel ways, of a frusto-conical engaging roll vertically mounted on each of said beams, a cylindrical roll also mounted on each beam adjacent to said frusto-conical roll, and means for im-

parting similar rotary motion to said rolls, substantially as set forth.

45 7. In a candy-molding machine, the combination, with parallel beams provided with ways, of a mold-rack at one end of the machine, feed-rolls on each beam adjacent said rack, and means for actuating said feed-rolls, substantially as set forth.

8. In a candy-molding machine, the combination, with parallel beams provided with ways, of suitable molds fed in said ways, a suitably-supported candy-containing hopper, and means for vertically adjusting said candy-containing hopper, substantially as set forth.

15 9. In a candy-molding machine, the combination of a rectangular frame supporting longitudinally-arranged beams, said beams being provided with ways, molds fed on said ways, a candy-containing hopper supported on said frame, a movable partition in said hopper, and a yoke-shaped support for said partition carried on said beam, substantially as set forth.

20 10. In a candy-molding machine, the combination of suitably-supported beams, a candy-containing hopper, supports for said hopper, standards on said beams having ways for guiding said supports, screw-shafts carried by said standards engaging said supports, means for simultaneously operating said screw-shafts for adjusting the hopper, said

25 hopper having a converging mouth, an adjustable lip for said mouth, and a resilient stricker inclined rearwardly from said mouth, substantially as set forth.

30 In testimony that I claim the foregoing as my invention I have signed my name in presence of two subscribing witnesses.

ANTON REICHE.
